UNITED STATES PATENT OFFICE.

WILLIAM FRANK M. HAWE, OF PITTSBURGH, PENNSYLVANIA, ASSIGNOR TO MAC-BETH-EVANS GLASS COMPANY, OF PITTSBURGH, PENNSYLVANIA, A CORPORATION OF PENNSYLVANIA.

DESIGN FOR AN INCLOSED LAMP-GLOBE.

56,431.

Specification for Design.

Patented Oct. 26, 1920.

Application filed June 23, 1919. Serial No. 306,259. Term of patent 14 years.

To all whom it may concern:

Be it known that I, WILLIAM FRANK M. HAWE, a citizen of the United States, residing at Pittsburgh, county of Allegheny, State of Pennsylvania, have invented a new, original, and ornamental Design for Inclosed Lamp-Globes, of which the following is a specification, reference being had to the accompanying drawing, forming a part thereof.

The figure is a side view of an inclosed lamp globe showing the new design.

I claim:

The ornamental design for an inclosed lamp globe, as shown.

WILLIAM FRANK M. HAWE.
